his ATTORNEY.

UNITED STATES PATENT OFFICE.

GEORGE HENNING, OF BEAVER FALLS, PENNSYLVANIA, ASSIGNOR OF TWO-THIRDS TO WILLIAM HALEY AND FRANK F. BRIERLY, OF SAME PLACE.

GLASS-PRESS.

SPECIFICATION forming part of Letters Patent No. 598,930, dated February 15, 1898.

Application filed April 24, 1897. Serial No. 633,817. (No model.)

To all whom it may concern:

Be it known that I, GEORGE HENNING, a citizen of the United States, residing at Beaver Falls, in the county of Beaver and State of Pennsylvania, have invented certain new and useful Improvements in Glass-Presses; and I do hereby declare the following to be a full, clear, and exact description of the invention, such as will enable others skilled in the art to which it appertains to make and use the same.

My invention relates to improvements in glass-presses of the power-operated class, the object being to secure increased efficiency of operation; and it consists in the novel features of construction, combination, and arrangement of parts, as hereinafter fully described, and specifically pointed out in the claims.

20 In the drawings, Figure 1 represents a front elevation of a press embodying my invention. Fig. 2 is a side elevation thereof. Fig. 3 is a detached view of the plunger-slide; Fig. 4, a side view of the eccentric and connections 25 for moving the cap-plate. Fig. 5 is a plan view of the gearing, &c., below the bed of the machine.

In the drawings, A represents the bed of the press, supported on or forming part of a 30 truck-frame a, provided with wheels a² for readily moving the press about. Upon the bed A are supported the upright rods or pillars b b, maintained in true position and alinement by braces c. The rods b b form 35 guides for a yoke or cross-head D, connected by rods e e to cranks E on a shaft F, journaled in the frame a. A second cross-head G, connected to yoke D, slides on the pillars b, being placed below the yoke D, and carries a 40 slide g, to which are secured two or more plungers H in the manner presently to be described. A pulley f on a shaft 2 is belted or otherwise suitably connected to a source of power, as a line-shaft pulley or the like, and 45 being geared by a suitable train of gears, as 6 7 8 9, to the shaft F serves to continuously rotate the same, the usual belt-shifting device in common use being also provided for stopping the machine at any moment. Obviously 50 each revolution of shaft F will cause the yoke

D, cross-head G, and plunger H to descend and rise once.

The slide g moves freely on the cross-head G, preferably on ball-bearings, and carries on its under side two chucks i i, through which 55 a right-and-left screw i² passes and serves to clamp the plunger H firmly in the chuck, thus enabling the plungers to be quickly changed.

An air-pipe J extends down on each side of the rod b on each side of the press and is 60 affixed rigidly to the press by suitable means—such, for instance, as the bars b², secured to the pipes J and rods b. The pipes J terminate above the cross-head G and receive pipes j, which are sleeved in the pipes J and slide 65 freely but not loosely therein. The pipes j are secured firmly to the cross-head G and move therewith and at their lower ends are provided with tips or nozzles j², which are directed toward the points occupied by the plungers H H when at the outward limit of their travel, as shown. A blast of air, artificially cooled or not, as may be preferred, is forced through the pipes J j, &c., and impinging directly on the plungers keeps them from be- 75 coming heated by the hot glass.

Attached to slide g is a slotted or grooved plate g², in which plays a pin k on an arm K, which is rigid with a short shaft l, supported in a bearing on the bed A and having an arm 80 K², which forms substantially a continuation of arm K and extends below the bed A, carrying at its lower end a second pin k², which engages a cam-groove m on a drum or disk M. The arms K and K² thus act substantially as 85 a lever pivoted on shaft l. The drum M might be carried by the shaft F, but I prefer to place it on an auxiliary shaft n, suitably supported, and which carries also a gear o, meshing with a gear or pinion o² on the shaft F. By thus placing the drum on a separate shaft it may be made smaller, the cam-groove simpler, and can also be rotated at a different rate of speed from that of shaft F, preferably at one-half the speed of shaft F. The pins k k² are 90 preferably provided with rollers k⁴, journaled thereon, to reduce the friction.

An adjusting-screw p is affixed to the cross-head G and threaded through an adjusting-nut p², seating upon the yoke D, screw p car- 100

rying intermediately a nut p^3 , between which and the yoke is interposed a heavy buffer-spring p^4 . By this screw the throw of the plungers is regulated.

5 An eccentric Q on shaft F reciprocates a rod q , which plays in a guide r and is attached to a cross-arm S . The cap-plate t of the mold T is connected by rods U at each end to the corresponding ends of the cross-arm S , the rods U passing through the bed A and carrying springs u , interposed between the plate t and bed A , as shown.

The operation of the machine is as follows: Assuming the mold T to be in place and filled 15 with molten glass, the rotation of shaft F by pulley f and their connecting train of gears will first cause the cam Q to draw down the cap-plate t , its projection t^2 seating in a corresponding recess in the mold. The further 20 rotation of shaft F will next cause the cranks E , which have meanwhile been drawing down the rods e , yoke D , cross-head G , and plungers H , to force the plunger which occupies the central position to enter the mold and form 25 the article. Then as the cranks E continue their revolution they lift the plunger, and as it rises above the cap-plate t the pin k^2 , which has meantime been traveling in the straight part of the cam-groove m on the continuously- 30 rotating drum M , now strikes the inclined part of the groove and moves the arms K^2 and K laterally, which, by means of the pin k traveling in plate g^2 , moves the slide g along cross-head G , so as to bring the second plunger in 35 the center and in line with the mold, which has in the meantime been removed, emptied, refilled, and replaced, the plungers thus acting alternately and always in the center, which prevents lateral strains on any of the parts. 40 As the air-pipes j and their nozzles travel with the cross-head, the plunger not acting is always being cooled and each plunger is subject to the cooling-blast about three-quarters of the time, which entirely prevents the overheating 45 of the plunger.

Obviously the plungers could be arranged to travel in a line at any angle to the lateral line shown or in a circle without departing from my invention, which, as regards this feature, consists, broadly, in employing a plurality of plungers which act successively and are subjected to cooling means while inactive or not in operation.

What I claim as my invention, and desire 55 to secure by Letters Patent, is—

1. In a glass-press the combination with the mechanism for moving the plunger to the mold, of a plurality of plungers, means for moving the same successively into the operative position, and means to supply a cooling-blast directed upon the inactive plungers, substantially as described.

2. In a glass-press the combination, with the mechanism for moving the plunger to the mold, of a plurality of plungers having a reciprocating movement, means for moving the

same successively into the operative position, and means to supply a cooling-blast directed upon the inactive plungers, substantially as described.

3. In a glass-press the combination with the mechanism for moving the plunger to the mold, of a plurality of plungers, means for moving the same successively into the operative position, and means to supply a cooling- 70 blast directed upon the inactive plungers and moving with the same, substantially as described.

4. In a glass-press the combination with the mechanism for moving the plunger to the 80 mold, of a movable cross-head, a plurality of plungers supported by and having lateral movement thereon, blast-nozzles attached to said cross-head and moving therewith, and means substantially as described for moving 85 the plungers successively into the operative position, substantially as described.

5. In a glass-press the combination with the mechanism for moving the plunger to the mold, of a movable cross-head, a slide secured 90 to and adapted to traverse thereon, a plurality of plungers attached to said slide, air-blast nozzles secured to said cross-head and moving therewith, and means for moving said slide intermittently to bring one of the plungers 95 into operative position, substantially as described.

6. In a glass-press the combination with the mechanism for moving the plunger to the mold, of a movable cross-head, a slide secured 100 to and adapted to traverse thereon, chucks attached to said slides, a plurality of plungers secured in said chucks, air-blast nozzles secured to said cross-head and moving therewith and directed upon the inactive plungers, 105 and means for moving said slide intermittently to bring one of the plungers into operative position and the inactive plungers into the blast from said nozzles, substantially as described.

7. In a glass-press the combination with the mechanism for moving the plunger to the mold, of a movable cross-head, a slide secured 110 to and adapted to traverse thereon, a plurality of plungers secured to said slide, air-blast 115 nozzles secured to said cross-head and moving therewith, a rotating surface having thereon a cam-groove, and an arm or lever engaging at one end said slide and at the other said cam-groove, whereby said slide is moved intermittently to bring one of the plungers into operative position and the others in range of the air-blast, substantially as described.

8. In a glass-press the combination with the mechanism for moving the plunger to the 120 mold, of a movable cross-head, a slide secured to and adapted to traverse thereon, a plurality of plungers secured to said slide, air-blast nozzles secured to said cross-head and moving therewith, a rotating surface having thereon 125 a cam-groove, a rock-shaft journaled on bearings on the machine bed or frame and having 130

an arm engaging said slide and an arm engaging said cam-groove, whereby said slide is moved intermittently to bring one of the plungers into operative position and the others in range of the air-blast, substantially as described.

9. In a glass-press the combination with the press-bed, the pillars *b* and braces *c*, a yoke sliding on said pillars, a crank-shaft having cranks connected to said yoke, and means for rotating said shaft, of a cross-head sliding on said pillars and connected to said yoke, a slide secured to said cross-head and adapted to traverse thereon, a plurality of plungers carried by said slide, air-blast nozzles secured to the cross-head and moving therewith, a rotating drum having a cam-groove on its periphery, a lever or rock-shaft having one arm engaging said slide and the other said cam-groove, for bringing said plungers successively into operative position, substantially as described.

10. In a glass-press the combination with the press-bed, the pillars *b* and braces *c*, a yoke sliding on said pillars, a crank-shaft having cranks connected to said yoke, and means for rotating said shaft, of a cross-head sliding on said pillars and connected to said yoke, a slide secured to said cross-head and adapted to traverse thereon, chucks attached to said slide, a plurality of plungers carried by said chucks, air-blast nozzles secured to the cross-head and moving therewith, said nozzles being directed toward the point occupied by the inactive plungers, a rotating drum geared to the crank-shaft and having a cam-groove on its periphery, a lever or rock-shaft having one arm engaging said slide and the other said cam-groove, for bringing said plungers successively into operative position, substantially as described.

11. In a glass-press the combination of the bed mounted on a frame having truck-wheels, pillars at each side of said bed, a yoke sliding on said pillars, a cross-head connected to said yoke and guiding on said pillars, a slide secured to said cross-head and traveling thereon, a plurality of plungers carried by said slide, stationary air-pipes rigid with the pillars, air-pipes secured to the cross-head and moving therewith, said moving air-pipes sliding in the stationary pipes and having nozzles directed to the point occupied by the inactive plungers, a crank-shaft journaled in said frame and having at each end a crank connected to the yoke, a shaft journaled in the frame and carrying a driving-pulley, a train of gears intergearing said pulley-shaft and crank-shaft, a shaft intergeared with the crank-shaft and carrying a drum having a cam-groove in its periphery, a lever or rock-shaft having one arm engaging said slide and the other engaging said cam-groove, for intermittently moving said plungers into operative position, and means for continuously

rotating said driving-pulley, substantially as described.

12. In a glass-press in combination with the reciprocating yoke and cross-head, the plunger, and a crank-shaft connected to said yoke for moving the plunger to the mold, an eccentric on said shaft, an eccentric-rod, a cross-arm carried by the eccentric-rod, a cap-plate arranged above the mold, and rods connecting the cap-plate and cross-arm, substantially as described.

13. In a glass-press in combination with the reciprocating yoke and cross-head, the plunger, and a crank-shaft connected to said yoke for moving the plunger to the mold, an eccentric on said shaft, an eccentric-rod, a cross-arm carried by the eccentric-rod, a cap-plate arranged above the mold, and having a projection adapted to enter a corresponding recess in the mold, and rods adjustably connecting the cap-plate to the cross-arm, substantially as described.

14. In a glass-press in combination with the reciprocating yoke and cross-head, the plunger, and a crank-shaft connected to said yoke for moving the plunger to the mold, an eccentric on said shaft, an eccentric-rod, a cross-arm carried by the eccentric-rod, a guide rigid with the bed in which said cross-arm plays, a cap-plate arranged above the mold and having a projection adapted to enter a corresponding recess in the mold, rods connecting the cap-plate and cross-arm, and a spring interposed between the cap-plate and the press-bed, substantially as described.

15. In combination with the reciprocating yoke and cross-head, a slide on said cross-head, plungers rigid with said slide, and a constantly-rotating shaft having on each end cranks connected to the yoke for moving the plungers to the mold, the drum geared to said shaft and rotating at half its speed, said drum having in its periphery a cam-groove formed into two straight portions and two inclined portions joining the straight portions, and a lever or rock-shaft having one arm engaging said cam-groove and the other engaging said slide, whereby the slides and plungers are moved one way only at each revolution of the cranks, substantially as described.

16. The combination with the reciprocating plunger-operating yoke and cross-head actuated by constantly-revolving cranks connected to the ends of said yoke, of a slide on said cross-head carrying a plunger at each extremity, a constantly-rotating cam-grooved drum, a lever or rock-shaft having one arm engaging said slide and the other engaging the cam-groove on said drum, and means substantially as described for synchronizing the motion of the crank-shaft and drum so that the plungers shall be moved alternately in each direction and the operative plunger shall be always centrally disposed, to equalize the strain, substantially as described.

17. In a glass-press the combination with the reciprocating plunger, operating-yoke and cross-head actuated by constantly-revolving cranks connected to the ends of said yoke, of
5 a slide having a ball-bearing on said cross-head and carrying a plunger at each end, and means substantially such as described for moving said slide alternately in each direction, so as to bring said plungers alternately

into operative position, substantially as described.

In testimony whereof I hereto affix my signature in presence of two witnesses.

GEORGE HENNING.
